UNITED STATES PATENT OFFICE.

WILLIAM H. VOSS, OF DAVENPORT, IOWA.

WASHING-MACHINE-OPERATING MECHANISM.

Application filed December 10, 1920. Serial No. 429,615.

To all whom it may concern:

Be it known that I, WILLIAM H. Voss, a citizen of the United States, residing at Davenport, in the county of Scott and State 5 of Iowa, have invented certain new and useful Improvements in Washing-Machine-Operating Mechanism, of which the following is a specification.

This invention relates to washing machine operating mechanism and more particularly to an improved clutch adapted to reduce as much as possible the shocks incident to starting and stopping the washer; and such further objects, advantages and 15 capabilities as will later more fully appear.

My invention further resides in the combination, construction and arrangement of parts illustrated in the accompanying drawings, and while I have shown therein a 20 preferred embodiment I desire the same to be understood as illustrative only and not as limiting my invention.

In the accompanying drawings, Fig. 1 is an end elevation of a washing machine, 25 showing my improvements applied thereto.

Fig. 2 is a sectional plan view of the machine shown in Fig. 1 to show the arrangement of my improvements.

Fig. 3 is a longitudinal section of the 30 clutch and mechanism associated therewith.

Fig. 4 is an end elevation of the structure shown in Fig. 3 when viewed from the left in said figure.

Fig. 5 is an inside face view of the cone 35 member shown in Figs. 3 and 4.

I have found that washing machines heretofore constructed, and more particularly machines of the oscillating tub type, have a tendency when starting or stopping to jerk 40 the machine excessively, making it unpleasant to operate the machine, besides being very hard on the machine itself. This difficulty I have overcome by inserting a friction clutch between the driving and driven mechanisms, my new clutch being shown in detail in Figs. 3, 4 and 5.

The frame member of my machine comprises a pair of cross bars 1 and 2, to which are suitably secured insulating blocks of 50 wood or other suitable material. In the present instance these blocks are shown as being held in place by means of a metallic clamping member 3 and a second metallic clamping member, (not shown), below cross bar 2, though they may be secured directly to the frame. Journalled in these blocks

is a shaft 5, on which is mounted the motor bracket 6. This bracket has an extension arm 7 at its lower end, to which is secured one end of a spring 8, the other end 60 of the spring being secured to an insulating bar 9, preferably of wood. Another bar 10 is secured to the diagonal braces 11, and through these two bars passes a bolt 12 having means for readily adjusting the tension of the spring 8, this being possible by reason of the fact that one end of the bar 9 is pivoted as shown at 13. It will therefore be seen that when the nut on bolt 12 is tightened up bar 9 is swung on its pivot 70 so as to put an increased tension on the spring 8.

The shaft of the motor M is provided with a belt wheel 15, over which passes an insulating belt 16, this belt also passing over a 75 drive wheel 17. This drive wheel is mounted on a shaft 18 which carries near its opposite end a gear 19, with which meshes a gear 20 on a shaft 21. This shaft also carries a gear 22 which meshes with a gear 23 80 on a shaft 24, by means of which a wringer shaft is driven. As shown in Fig. 3 shaft 21 is provided with a spline or splines 25 to prevent the rotation of gears 20 and 22. These gears may either be rigidly secured 85 to the shaft and may reciprocate with it when it is moved axially to cause the clutch to engage or be disengaged, or they may be provided with means to prevent their axial movement, thereby causing the shaft to slide 90 therethrough. Any desired means may be used to accomplish this result, such, for example, as kerfs cut in the gear hubs and co-operating with projections rigidly carried by a frame member. It will be obvious 95 that if the gears move with the shaft 21 the intermeshing gears should have sufficient width so that the engaging faces of the gear teeth will have a substantial surface in engagement, both when the clutch is thrown in 100 and out.

A pair of collars 26 is secured to shaft 21 intermediate its ends and is engaged by the forked end 27 of a lever 28 mounted on frame cross-bar 2 by means of a bracket 29. 105 The tension of a spring 30 secured at one end to the frame and at its opposite end to the lever 28 normally actuates the shaft 21 to the right as shown in Fig. 3, thereby holding clutch cone 31 in engagement with 110 the inner surface of clutch member 32. The bearing member 33, secured to the cross bar

2, normally supports shaft 21 for rotation. Also supported on this cross bar 2 is a member 34 having one end turned up, as at 35, to engage a kerf in the hub of clutch cup 32, 5 as shown best in Fig. 3. The clutch cone 31 is provided on its inner surface with a plurality of projections 37 adapted to hold in place a plurality of wood or other suitable blocks 38. Preferably these blocks are 10 of wood boiled in tallow for giving the blocks a smooth frictional engagement with the cup 32. The outer faces, radially of these blocks, are both curved and bevelled to fit the inner concave surface of the clutch 15 cup 32, so that when the clutch is thrown in these faces will closely engage the face of the cup, thereby causing the same to be driven. Suitably secured to the periphery of the clutch cup 32 is a cross bar 39 which 20 carries a crank pin 40 which latter passes through and is secured in a pitman 41, by means of which the tub is oscillated, as will be understood by reference to Fig. 1. Reference to Fig. 4 will show that screws are 25 provided for holding the blocks 38 in position on the member 31, of which they, in reality, constitute a part.

To throw the clutch out of operation there is provided a handle 42 secured to a shaft 30 43 which has adjacent its lower end a crank arm 44 to which is secured a link 45, another portion of this link being secured to lever 28 as shown in Fig. 2. Any suitable means is provided for holding the crank 42 and 35 shaft 43 from rotation under the influence of spring 30. It will be seen that by reason of this locking means the clutch parts can be kept out of engagement when desired, and that when it is desired to start the machine the clutch can be thrown in as slowly as desired, the spring 30 resiliently holding the clutch members in engagement.

It is obvious that if the clutch is thrown in slowly the machine will start up without 40 45 any jerking or jolting whatever, but I wish also to point out that with my construction

it is possible to throw the clutch in quickly, without any particular attention thereto, and that no disagreeable jolting or jerking of the machine will result. I should perhaps state that if desired the cross bar 39 may be formed as a cover plate so that member 31 is entirely covered over and enclosed, though this is not considered necessary.

It is of course understood that the specific 55 description of a structure set forth above may be departed from without departing from the spirit of my invention as set forth in this specification and the appended claims.

Having now described my invention, I claim:

1. In a machine of the character described, having driving means and driven means, a clutch adapted to connect said means, said clutch comprising a cup member, a cross bar secured to the cup member, a crank pin fixed to the cross bar, a cone member in the cup member and co-operable therewith for clutching operation, a driving shaft secured to the cone member, and means for shifting the cone member and the shaft, for clutching and unclutching the cup and cone members. 70

2. In a device of the character described, a drive shaft and a driven element, a clutch 75 adapted to connect said shaft and element, said clutch comprising a cup member having a conical inner surface, a cooperative clutch member on said drive shaft and concentrically within said cup member and provided on its face with wooden blocks impregnated with tallow, said blocks having tapered edge surfaces cooperating with the conical inner surface of said cup member for the clutching operation, and means for shifting said drive shaft endwise for clutching and unclutching said cup and clutch member. 80 85

In witness whereof, I hereunto subscribe my name to this specification.

WILLIAM H. VOSS.
